LETTERING DEVICE

Robert W. Anderson, Weehawken, N. J., assignor
to Keuffel & Esser Company, Hoboken, N. J., a
corporation of New Jersey

Application February 6, 1948, Serial No. 6,576

11 Claims. (Cl. 33—23)

1

This invention relates to lettering or scribing devices of the kind in which a writing instrument is carried by a scribe member and is directed over the surface to be written upon by a tracer pin moving in character grooves or the like formed in a template and by a tail pin movable in a groove or the like parallel with the line of lettering. The writing instrument carried by the scribe may be either a pen, pencil or ball point pen.

Devices of the character described, such as those shown in U. S. Patents 2,011,195, 2,050,057, 2,050,058, to A. W. Keuffel have heretofore had an inherent limitation in their construction, in that a straight line was not produced by the writing instrument when the tracer pin followed a straight line groove in the template. In characters of small size this distortion of a straight line may have been of barely noticeable or negligible magnitude. In a device used for larger characters, however, it was frequently necessary to distort the characters on the template so that the characters formed by the writing instrument would have no noticeable distortion. The distortion of characters became even more pronounced when using instruments provided with an adjustable arm for making inclined letters.

One object of the invention is to provide a lettering device in which the writing instrument travels in a straight line when the tracer pin travels in a straight line.

Another object of the invention is to provide a lettering device with an adjustable arm capable of forming inclined letters of various slopes but in which the writing instrument travels in a straight line when the tracer pin travels in a straight line regardless of the slope of the lettering.

Another object of the invention is to simplify the production of templates for lettering devices of the type described by providing a scribe which is capable of forming undistorted characters, from a template provided with undistorted characters.

Another object of the invention is to simplify the production of templates having more than one row of letters or characters on their faces by making it possible to incline several rows of letters backward at the same angle and still have the scribe produce undistorted vertical letters from each row.

Another object of the invention is to provide a simplified means for securing the writing instrument to the scribe member.

Another object of the invention is to provide a writing instrument

2

a lettering device capable of forming inclined letters of various slopes directly proportional to adjustment of the movable arm and having means for indicating the slope of the inclined letters clearly and simply.

These and other objects of the invention and the means for their attainment will be more apparent from the following detailed description taken in connection with the accompanying drawings illustrating two preferred embodiments of the invention and in which:

Figure I is a view in plan of an embodiment for drawing vertical letters or characters.

Figure II is a view in elevation of the embodiment shown in Figure I.

Figure III is a view in side elevation of the embodiment shown in Figure I.

Figure IV is a view in enlarged plan showing the details of the writing instrument holding means.

Figure V is a diagrammatic sketch showing the geometrical arrangement of the essential parts in Figure I.

Figure VI is a view in plan of an embodiment provided with adjustable means for drawing slanted letters or characters at various slopes.

Figure VII is a view in elevation of the embodiment shown in Figure VI.

Figure VIII is a view in side elevation of the embodiment shown in Figure VI.

Figure IX is a diagrammatic sketch showing the geometrical arrangement of the essential parts of the scribe and template shown in Figure VI.

Referring to Figures I, II, and III the template 2 is provided with a tail pin groove 4 and character grooves 6. The character grooves 6 are in the two rows of characters 3 and 5. In the embodiment shown row 3 has the lower case or small letters and row 2 has the upper case or capital letters. The tail pin and character grooves may take a variety of forms or may even be raised lines providing a suitable follower is provided. No limitation is intended herein after by use of the term groove.

The body member 8 is made up of a knob 10 fastened as by screws 14 to the scribe plate 12. The scribe plate 12 has three arms, the tail pin arm 16, the tracer pin arm 18 and the writing instrument arm 20, which in this embodiment are integral therewith. The tail pin arm 16 carries the tail pin 22 which operates in the tail pin groove 4 of the template 2. The tracer pin arm 18 carries the tracer pin 24 which operates in the character grooves 6. The writing instrument

arm 20 carries the writing instrument which in this embodiment is the pen 26.

The pen 26 is removable and is held in position by the clamp screw 28 on the writing instrument arm 20. The clamp slot 30 from the edge of the arm 20 extends substantially parallel to the upper edge of the writing instrument arm 20 into the hole 31 which receives the pen 26 forming a clamp strap 32 which is an integral part of the writing instrument arm 20 and the scribe plate 42. When the clamp screw 28 is tightened, it wraps the clamp strap 32 around the pen 26 holding it firmly in place.

Referring to Figure V, the body member 8 (not shown) is formed so that the tail pin 22, tracer pin 24, and writing instrument 26 are the vertices of a right triangle, the side 24-26 being perpendicular to the side 24-22, and the angle α between side 22-24 and side 22-26 being of a predetermined value. The tail pin groove 4 is shown containing the tail pin 22 as usual. To illustrate the geometrical relationships the tracer pin 24 is also shown in the tail pin groove 4 because the character groove 7 is assumed to continue until it intersects the tail pin groove 4. The straight character groove 7 which would be the character groove for the vertical part of the capital letter "I" or the numeral "1" or the vertical line in any letter is formed in the template so that the angle α' between the character groove 7 and the vertical line 34 is of the same predetermined value as angle α . The vertical line 34 which is the path followed by the writing instrument 26 when the tracer pin follows the straight character groove 7 as described is perpendicular to the tail pin groove 4.

If the device is made according to the geometric arrangement shown in Figure V and described above, when the tracer pin 24 moves along the character groove 7 or along any portion of the groove 7 within the limits permitted by the device and the tail pin 22 moves along the tail pin groove 4, the writing instrument will move along the vertical line 34. If the character groove 7 is a straight line the line drawn by the drawing instrument will also be a straight line. It is immaterial how far from the tail pin groove 4 the tracing pin 24 moves along the straight line 7, the writing instrument 26 will always follow the vertical line 34. Therefore the line 7 could include vertical portions of characters in both rows 3 and 5, for example the vertical sides of the letters D and d could be produced by the writing instrument arm along the line 34 of Figure V. Furthermore it is not necessary that the vertical parts of the letters from both rows lie on the same straight line, they may lie in any line parallel to the line 7 which will be inclined at an angle, equal to angles α and α' from the vertical. Similarly if the tracer pin 24 follows a groove representing a character such as a letter O in either row but which is backwardly inclined by an angle equal to the angles α and α' the writing instrument will trace the character or letter O in an undistorted vertical position.

In Figure VI a template 2 is again shown provided with a tail pin groove 4 and character grooves 6. The scribe member 38 in this embodiment is made up of three main parts, the knob 40, the scribe plate 42 and the adjustable writing instrument arm 50. The knob 40 is securely fastened to the scribe plate 42 as by the screws 44. The adjustable writing instrument arm 50 is rotatable below the knob 40 about the

pin 45 which is secured to the scribe plate 42.

The scribe plate 42 is provided with two arms, the tail pin arm 46, and the tracer pin arm 48. The tail pin arm 46 carries the tail pin 52 which is slidable in the tail pin groove 4. A weight not shown may be provided on the tail pin arm 46 in order to hold the tail pin 52 in the tail pin groove 4. The tracer pin arm 48 carries the tracer pin 54 which operates in the character grooves 6. The adjustable writing instrument arm 50 carries the writing instrument which as shown in this embodiment is a pen 56. The pen 56 is removable and is held in position on the adjustable writing instrument arm 50 by the clamp screw 58, as in the Figure I embodiment.

The motion of the adjustable writing instrument arm 50 is limited by the stop pin 70 carried by the scribe plate 42 acting in the arcuate slot 72 provided in the adjustable writing instrument arm 50. The stop pin 70 is provided with a head 74 (see Fig. VII). The stop pin head 74 rests on the scribe plate 42 which is provided with a key pin 78 firmly attached thereto and fitting in a slot in the stop pin head 74 to prevent any rotation of the stop pin 70. The clamp plate 79 is provided below the movable writing instrument arm 50 and is prevented from rotating by the pivot pin 45 and stop pin 70 both of which pass through it. The lower end of the stop pin 70 is threaded to receive the threaded tightening lever 80. The threaded tightening lever 80 clamps the adjustable writing instrument arm 50, between the scribe plate 42 and the clamp plate 79 to hold the adjustable writing instrument arm 50 in adjusted position. The upper side of the clamp plate 79 may be provided with a roughened surface to increase friction and more securely hold the adjustable writing instrument arm 50.

The scribe plate 42 is provided with an angular scale 82. The adjustable writing instrument arm 50 is provided with an index mark 84 adjacent to the angular scale 82. In this embodiment the index mark is a pin shaped to a V section with the vertex adjacent to the scale 82. Alternatively, the scale 82 may be provided on a cylindrical edge of the scribe plate 42 and the index mark may be a line on the edge of the movable writing instrument arm 50. Many other arrangements of scale and index mark are possible. The angular scale 82 is calibrated to indicate the forward slope of the characters produced with the device in the adjusted position of the adjustable writing instrument arm. The calibrations are in angles which may be numbered to one half the actual angular rotation of the movable writing instrument arm 50 in a manner and for reasons which will subsequently be described.

Referring to Figure IX the tail pin 52, tracer pin 54, and writing instrument 56 are shown as the vertices of a right triangle equivalent to that shown in Figure V. The side 54-56 is perpendicular to the side 54-52 and the side 52-54 forms an angle α of predetermined value with side 52-56. The tail pin groove 4 is shown as a line containing the tail pin 52. A character groove 7 is shown containing the tracer pin 54 and making an angle α' of the same predetermined value as angle α with the vertical line 34 which is perpendicular to the tail pin groove 4.

As previously stated in connection with Figure V a fixed device having the geometric arrangement so far described will draw straight undistorted vertical characters from a template pro-

vided with straight undistorted characters which may be in more than one row on the template but must be backwardly inclined an amount equal to the angle α .

In the embodiment shown in Figure VI and diagrammatically in Figure IX a pivot pin 45 is provided which is at the center or point of bisection of the line 56-52. By turning the adjustable writing instrument arm about the pin 45 through an angle b the writing instrument or pen 56 is brought to an adjusted position 56'. The points 56 and 56' in Figure IX are equally distant from the point 45.

If the device is made according to the described geometric arrangement, the pen in its adjusted position 56' will move along a straight line 64 inclined forward from the vertical line 34 by an angle equal to $\frac{1}{2}b$, when the tracer pin follows the straight line 7 and the tail pin 52 follows the straight line 4. Therefore, such a device with the adjustable writing instrument arm 50 in adjusted position having been turned thru an angle b so that the writing instrument 53 is in adjusted position 53' will draw straight undistorted characters forwardly inclined by an angle $\frac{1}{2}b$ from a template provided with straight undistorted characters which may lie in more than one row on the template but must be backwardly inclined an amount equal to the angle α .

In agreement with the geometric facts illustrated in Figure IX, the angular scale 82 shown in Figure VI should be calibrated to read one half the angle through which the adjustable writing instrument arm is actually turned.

Having thus described the invention what is claimed is:

1. In a scribe for drawing characters from a template having character grooves and a tail pin groove, the combination of a tail pin, a tracer pin, and means for holding a writing instrument, each substantially at the vertices of a right triangle, said tracer pin being located at the right angle vertex.

2. In an adjustable scribe for drawing characters from a template having character grooves and a tail pin groove, the combination of a tail pin, a tracer pin, and means for holding a writing instrument, each substantially at the vertices of a right triangle when the scribe is adjusted for drawing erect characters, said tracer pin being located at the right angle vertex, a scribe body member having said tail pin and tracer pin secured thereto, an adjustable member carrying said means for holding a writing instrument, and pivot means placed at the midpoint of the hypotenuse of said right triangle about which said adjustable member may be rotated, and means to hold said adjustable member in an adjusted position.

3. In an adjustable scribe for drawing characters from a template having character grooves and a tail pin groove, the combination of a tail pin, a tracer pin, and means for holding a writing instrument, each substantially at the vertices of a right triangle when the scribe is adjusted for drawing erect characters, said tracer pin being located at the right angle vertex, a scribe body member having said tail pin and tracer pin secured thereto, an adjustable member carrying said means for holding a writing instrument, and pivot means placed at the midpoint of the hypotenuse of said right triangle about which said adjustable member may be rotated, means to hold said adjustable member in an adjusted posi-

tion, and a scale to show the position of said adjustable member.

4. A scribing device comprising a template having character grooves and a tail pin groove, and a scribe having the combination of a tail pin, a tracer pin and means for holding a writing instrument, each substantially at the vertices of a right triangle, said tracer being located at the right angle vertex.

5. A scribing device comprising a template having character grooves inclined backwardly at a predetermined angle from a vertical position and a tail pin groove, and a scribe having the combination of a tail pin, a tracer pin and means for holding a writing instrument, each substantially at the vertices of a right triangle, said tracer pin being located at the right angle vertex and the angle at the tail pin vertex being substantially equal to said predetermined angle.

6. An adjustable scribing device comprising a template having character grooves and a tail pin groove, and a scribe having the combination of a tail pin, a tracer pin, and means for holding a writing instrument, each substantially at the vertices of a right triangle when the scribe is adjusted for drawing erect characters, said tracer pin being located at the right angle vertex, a scribe body member having said tail pin and tracer pin secured thereto, an adjustable member carrying said means for holding a writing instrument, and pivot means placed at the midpoint of the hypotenuse of said right triangle about which said adjustable member may be rotated, and means to hold said adjustable member in adjusted position.

7. An adjustable scribing device comprising a template having character grooves and a tail pin groove, and a scribe having the combination of a tail pin, a tracer pin, and means for holding a writing instrument, each substantially at the vertices of a right triangle when the scribe is adjusted for drawing erect characters, said tracer pin being located at the right angle vertex, a scribe body member having said tail pin and tracer pin secured thereto, an adjustable member carrying said means for holding a writing instrument, and pivot means placed at the midpoint of the hypotenuse of said right triangle about which said adjustable member may be rotated, means to hold said adjustable member in adjusted position, and a scale to show the position of said adjustable member.

8. An adjustable scribing device comprising a template having character grooves inclined backwardly at a predetermined angle from a vertical position and a tail pin groove, and a scribe having the combination of a tail pin, a tracer pin, and means for holding a writing instrument, each substantially at the vertices of a right triangle when the scribe is adjusted for drawing erect characters, said tracer pin being located at the right angle vertex, a scribe body member having said tail pin and tracer pin secured thereto, an adjustable member carrying said means for holding a writing instrument, and pivot means placed at the midpoint of the hypotenuse of said right triangle about which said adjustable member may be rotated, and means to hold said adjustable member in adjusted position and the angle at the tail pin vertex being substantially equal to said predetermined angle.

9. In a scribe for drawing characters from a template having character grooves and a tail pin groove, the combination of a knob and a scribe plate secured thereto and carrying a tail pin, a

tracer pin and means for holding a writing instrument, each substantially at the vertices of a right triangle, said tracer pin being located at the right angle vertex, said means for holding a writing instrument comprising a hole for receiving the writing instrument a slot extending from said hole to an edge of said scribe forming a straplike member and clamp means acting to wrap said straplike member around said writing instrument and hold it in place.

10. In a template for use with a scribe for drawing characters therefrom and having a tail pin, a tracer pin, and means for holding a writing instrument, each substantially at the vertices of a right triangle, the tracer pin being located at the right angle vertex, and the angle at the tail pin vertex being of a predetermined value, the combination of a horizontal tail pin groove and character grooves forming characters in a plurality of horizontal rows, said characters in all rows being inclined backwardly from the vertical at an angle of the same predetermined value.

11. In an adjustable scribe for drawing char-

acters from a template having character grooves and a tail pin groove, the combination of a tail pin, a tracer pin and means holding a writing instrument each substantially at the vertices of a right triangle when the scribe is adjusted for drawing erect characters, said tracer pin being located at the right angle vertex, one of said elements of the combination being adjustable away from a vertex of said right triangle for drawing inclined characters and means to hold said adjustable element in adjusted position.
